UNITED STATES PATENT OFFICE

2,393,555

BAR FOR CARBON CARRIERS

Walter E. Oliver, Quincy, Mass., assignor to
American Register Company, Boston, Mass., a
corporation of Massachusetts

Application November 4, 1943, Serial No. 508,939

10 Claims. (Cl. 282—1)

This invention relates to carbon carriers such as are used for continuous strip stationery.

When continuous strip stationery is used for producing a number of copies by means of a typewriter, it is usual to provide a "carrier" on which are supported a number of carbon sheets (the whole being sometimes termed a "jacket"), with which sheets the record strips are interleaved. The carrier and carbons move with the strips while one unit length of the latter is being inscribed but are retained in the machine while the inscribed portion is pulled forward and torn off, the carbons after suitable readjustment about the platen being ready for use with the succeeding unit length of the record strips. Such a carrier desirably carries a bar at its trailing edge, conveniently detachable to permit its use with a plurality of carriers, serving among other things as a stop to prevent the carrier and its carbons from being fed out of the typewriter and also as a convenient grasping handle for manipulating the carrier and carbons.

The object of the invention is to provide a simple and durable bar which may be quickly attached to or detached from the carrier.

My invention will be well understood in connection with the following description of the illustrative embodiment thereof shown by way of example in the accompanying drawing, wherein:

Fig. 1 is an elevation of the carrier with attached bar. If we imagine the parts as held up and ready to be inserted in the typewriter at the rear of the platen roll, the point of view is that of a person standing at the rear of the typewriting machine;

Fig. 2 is a top plan view of the parts shown in Fig. 1;

Fig. 3 is an elevation of the bar detached, viewed from the same side as in Fig. 1;

Fig. 4 is a plan view corresponding to Fig. 2 showing how the bar may be secured to a carrier; and

Fig. 5 is a vertical sectional view through the carrier with record strips interleaved with the carbons.

While the form of bar illustrated might be utilized with various constructions of carrier if provided with openings (preferably rectangular) adjacent their side edges at the rear or trailing edge, I herein show it as applied to a carrier such as is shown and described in the patent to Fader 2,320,918 June 1, 1943.

The carrier shown comprises a rectangular sheet 6 of thin tough flexible material such, for example, as tough paper or cloth. The leading

end portion of the sheet 6 (lower end viewing Fig. 1) is provided with a series of slits 8 parallel to the front edge suitably spaced from each other and which are of a length slightly wider than the record strips to be manifolded. The slits terminate short of the side edges of the sheet and the marginal portions 9 of the sheet beyond the ends of the slits are folded over and adhesively secured to the body of the sheet throughout an area extending from approximately the rearmost slit to the end of the marginal portions 9, so that the marginal portions 9 thus adhesively secured to the body of the sheet 6 form a substantial reinforcement for the side edge portions of the sheet.

The slits 8 and the forward edge of the sheet 6 define bars 10 about which the rear ends of transfer or carbon sheets 12 are wrapped and adhesively secured, as best illustrated in Fig. 5. In use form strips 14 with the exception of the outermost strip are threaded through the slits 8, as seen in Fig. 5.

The body of the sheet and the folded-over marginal portions are provided with rectangular apertures 16 adjacent the side margins and the straight rear edge of the sheet which provide for the attachment of the bar which is shown detached in Fig. 3 and which I shall next describe. The description just given is merely a description of a carrier as disclosed in the Fader Patent 2,320,918.

In accordance with my invention I provide a bar detachably secured along the rear edge of the carrier, the outer ends of which bar are provided with outwardly opening pockets into which the outer margins of the openings 16 are received and in which said margins seat, these end portions being maintained in the normal position of Figs. 1 and 2 by resiliently yieldable means which may be stressed to bring the end portions closer together to permit easy withdrawal of the end of the bar from about the margins or, conversely, easy engagement of the bar with such margins when the bar is to be applied initially to a given carrier.

In the embodiment of the invention shown the front wall of this pocket is formed by the back of the shank of an inwardly facing hook 18 of flat sheet metal, the hook being of a size to pass through the opening 16 from the rear, viewing Fig. 1. The metal is rebent to form the bill of the hook, and the throat of the hook provides a guide for the edges of the record strips which in use overlie the nearer face of the sheet 6 (see Fig. 5). Connecting the shanks of the hooks is a flat strip

of spring metal 20, the length of which (see Fig. 2) is conveniently equal to the distance between the relatively remote edges of the openings 16 so that in the normal operating position of these parts (Figs. 1 and 2) these edges seat on the ends of the strip, these ends forming the bottoms of the pockets above referred to. The hooks 18 and strip 20 may be secured together by screws 22 which take into back pieces 24, herein lengths of half-round wood which are spaced from the backs of the shanks of the hooks by the thickness of the metal of the strip 20, thus providing the rear wall of the pocket above referred to. Preferably, as best seen in Fig. 2, the ends of the pieces 24 are chamfered outwardly and rearwardly at 26 to provide a broad entrance-way to this pocket. The pieces 24 being formed of wood, while light, are relatively bulky and provide an efficient stop to prevent the sheet 6 and its attached carbons 12 from being fed around the platen of the typewriter and out at the front and also provide a convenient grasping handle for the assembly. Preferably the inner ends of the pieces 24 extend inwardly in substantial juxtaposition to each other to provide in effect, as shown in Fig. 2, a single bar-like projection across the width of the carrier, but these ends are unattached to the spring strip 20 at their inner ends, which construction permits the bar as a whole to be laterally flexed when the strip 20 is bent, as illustrated in Fig. 4 for the purpose now to be described.

The operation will be clear from Fig. 4, wherein the bar is being attached to sheet 6 by passage of the hooked portions 18 through the holes 16. One of the hooks 18 obviously can easily be introduced through the right-hand opening 16 so that the margin of the sheet outward of that opening enters the pocket defined by the back of the hook and the opposed face of the piece 24. The bar is then flexed in the manner indicated in Fig. 4 so that the distance between the two hooks 18 is shortened and, if necessary with some slight downward deflection of the left-hand edge of the sheet 6, the end of the left-hand hook 18 may be passed through the left-hand opening 16 and the bar permitted to spring back to the position of Fig. 2, the margins of the sheet entering the pockets and being seated therein as shown in Fig. 2. As best seen in Fig. 1, the pockets are of a slit-like character and have front and back walls which in use overlie the front and back faces of the marginal portion of the carrier sheet 6 outwardly of the openings 16, the pockets being normally coplanar. As will be apparent from Fig. 4, the chamfer 26 facilitates the engaging action. To remove the bar it is flexed to direct the bill of the hook toward the opening and permit the hook to be withdrawn through the opening.

The bar is simple to make and rugged in construction and may be quickly and easily manipulated in use.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A bar for carbon carriers as utilized with continuous strip stationery comprising a pair of

hook-shaped guide members at the ends thereof proportioned to pass through marginal openings in the carrier, a flat spring strip connecting the stems of the hooks, and members at the backs of the hooks defining with the backs of said stems spaces opening outwardly in the directions of the ends of the bar to receive the margins of the carrier outward of said openings.

2. A bar for carbon carriers as utilized with continuous strip stationary comprising a pair of hook-shaped guide members at the ends thereof proportioned to pass through marginal openings in the carrier, a flat spring strip connecting the stems of the hooks, and members at the backs of the hooks defining with the backs of said stems spaces opening outwardly in the directions of the ends of the bar to receive the margins of the carrier outward of said openings, the inner ends of said members being free of the spring strip and extending into substantial end to end juxtaposition to provide when the spring strip is straight in effect a uniform bar across a face of the carrier.

3. A bar for carbon carriers as utilized with continuous strip stationery comprising a pair of hook-shaped guide members at the ends thereof proportioned to pass through marginal openings in the carrier, a flat spring strip connecting the stems of the hooks, and members at the backs of the hooks defining with the backs of said stems spaces opening outwardly in the directions of the ends of the bar to receive the margins of the carrier outward of said openings, the inner ends of said members being free of the spring strip and corresponding in length to the distance between remote margins of the openings and providing by its ends stops therefor.

4. A bar for carbon carriers as utilized with continuous strip stationery comprising spaced elements at the ends thereof, which provide spaces between them opening outwardly to the ends of the bar one of which elements is proportioned to pass through marginal openings of the carrier to provide for the reception of the marginal portions of said carrier outward of the openings in the spaces between the elements, the bar as a whole being laterally flexible to permit the introduction of said portions endwise into said space.

5. A bar for carbon carriers as utilized with continuous strip stationery comprising spaced elements at the ends thereof, which provide spaces between them opening outwardly to the ends of the bar one of which elements is proportioned to pass through marginal openings of the carrier to provide for the reception of the marginal portions of said carrier outward of the openings in the spaces between the elements, the bar as a whole being laterally flexible to permit the introduction of said portions endwise into said space, the elements which pass through the openings being rebent to provide edge guides for the record strips.

6. A bar for a carbon carrier of the kind used in making manifold records with continuous strip stationery and having openings near its side edges, the bar having end portions presenting outwardly opening slit-like pockets to receive the outer margins of the openings seated therein, the pockets having front and back walls of extended area to overlie the front and rear faces of the marginal portion of the carrier, the bar also comprising spring means normally maintaining its said end portions spread apart and seated on said margins but capable of being stressed to draw said end portions nearer together to provide for the engagement or release of said margins.

7. A bar for a carbon carrier which has openings near its side edges, the bar comprising inwardly opening hooks at the ends thereof providing guides for the record strips, said hooks being proportioned to pass through the openings and presenting at the backs of said hooks relatively permanently positioned parts defining with said backs pockets opening outwardly at the ends of the bar to receive the outer margins of the openings, the bar comprising spring means normally maintaining said pockets spaced to seat said margins therein but capable of being stressed to draw the pockets together to provide for the withdrawal of the hooks from said openings and their introduction through the same.

8. A bar for a carbon carrier which has openings near its side edges comprising aligned wooden pieces supported on the ends of a flexible and resilient flat strip and hook-shaped guides for the edges of record strips at the ends of the bar, there being a slight clearance between the backs of the hooks and the opposed faces of said pieces defining spaces opening outwardly toward the ends of the bar to permit the hooks to pass through the openings of the carrier and overlie 25

the margins thereof outwardly of those openings.

9. A bar for a carbon carrier which has openings near its side edges, the bar having transverse shoulders corresponding in spacing to the spacing of the remote edges of said openings and overhanging portions extending lengthwise of the bar outwardly from said shoulders and of a transverse section permitting passage through the openings, the bar as a whole being constructed to permit lateral flexing thereof to draw the ends of said portions, which lie outward of the shoulders, nearer together to provide for their passage into or withdrawal from the openings.

10. A bar for a carbon carrier of the kind used in making manifold records with continuous strip stationery having openings near its side edges, the bar having end portions formed with normally coplanar inwardly extending pockets opening to the extremities of the bar, the parts of said end portions at one side of said plane being of a size to pass the openings whereby the outer margins of the openings may be received in the pockets, the bar being as a whole resiliently flexible laterally of such plane.

WALTER E. OLIVER.
